UNITED STATES PATENT OFFICE

131,143

DESIGN FOR A COMBINED AIR FILTER AND LIGHT OR THE LIKE

Svend Bramsen, Chicago, Ill., assignor to Binks
Manufacturing Company, Chicago, Ill., a cor-
poration of Delaware

Application December 5, 1941, Serial No. 104,501

Term of patent 7 years

To all whom it may concern:

Be it known that I, Svend Bramsen, a citizen
of the United States and residing at Chicago,
county of Cook, and State of Illinois, have in-
vented a new, original, and ornamental Design
for a Combined Air Filter and Light or the like,
of which the following is a specification, refer-
ence being made to the accompanying drawings
forming a part thereof.

Fig. 1 is a view in perspective of a combined

air filter and light or the like, showing my new
design.

Fig. 2 is a similar view with the device tilted
to show features underneath;

Fig. 3 is a side elevational view thereof; and,

Fig. 4 is a top plan view thereof.

I claim:

The ornamental design for a combined air filter
and light or the like, substantially as shown.

SVEND BRAMSEN.
